UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPEWRITING MACHINE.

Application filed April 12, 1923. Serial No. 631,494.

To all whom it may concern:

Be it known that I, GEORGE A. SEIB, citizen of the United States, and resident of Ilion, in the county of Herkimer and State of New York, have invented certain new and useful Improvements in Typewriting Machines, of which the following is a specification.

My invention relates to typewriting machines, and more particularly to the type actions thereof.

In typewriting machines wherein the pivoted type bars are mounted in a segmentally arranged series, it has been found difficult to provide sufficient room in which to mount the requisite number of type bars and yet provide sufficient room between them in the basket, so that in operation conflict between adjacent bars may be avoided. This is particularly true where the type bars of the entire system are of uniform length and are mounted side by side with their pivotal centers in a single arc or plane, as for example where the type bars are mounted in guide-slots of a segment to turn on a single pivot wire with all parts of the latter disposed in the same plane.

The main object of the present invention is to provide a simple and efficient construction by which these difficulties may be overcome and which is easy to manufacture.

A further object of the invention is to enable the features of my invention to be incorporated in existing forms of typewriting machines without material modification thereof and without modifying the appearance of the machine.

To the above and other ends which will hereinafter appear, my invention consists in the features of construction, arrangements of parts and combinations of devices set forth in the following specification and particularly pointed out in the appended claims.

In the accompanying drawings, wherein like reference characters indicate corresponding parts in the various views,

Figure 1 is a fragmentary fore and aft vertical sectional view of a typewriting machine embodying my invention.

Figure 2 is a detail fragmentary front elevation of a portion of the same.

Figures 3 and 4 are detail fragmentary plan views, partly in section, and showing

two left-hand and two right-hand type bars, respectively.

I have shown my invention in the present instance embodied in an Improved #10 Remington machine in which the invention may be incorporated with but slight modification of the machine as it now exists. It should be understood, however, that the invention is not restricted to its embodiment in such machines, but may be employed in the various styles of typewriting machines wherever found available.

The present invention is in the nature of an improvement on that disclosed in my Patent #1,446,935, dated Feb. 27, 1923, and has some of the same general objects in view, but provides a construction which may be manufactured with less difficulty than the said patented construction, as will hereinafter more clearly appear.

In the accompanying drawings, I have illustrated only so much of the machine as may be necessary to arrive at an understanding of the invention.

The frame of the machine comprises a base 1, corner posts 2, and a top plate 3, over which the carriage (not shown) travels from side to side of the machine and carries a platen 4. Segmentally arranged upwardly and rearwardly striking sheet metal type bars 5 of uniform length are mounted at their heels in guide slots 6 in a type bar segment 7 on a pivot wire 8 carried by the segment. The arc-shaped pivot wire is disposed in an upright plane, and all parts thereof are arranged at a uniform distance from the point of convergence 9 of the type bars. From an inspection of Fig. 2, it will be seen that the distance between adjacent slots in the segment gradually increases from the center to the sides of the system. Each type bar moves from its segmental type rest 10 to the common printing point 11 through about 90°. In moving to the printing position each type bar enters between opposite jaws of the usual type bar center guide 12 secured to the segment 7.

The type bars may be actuated by any suitable means, those shown in the present instance comprising spring returned key levers 13 and bell crank sub-levers 14. Each key lever is fulcrumed on a bar 15 fixed to the base 1 of the machine, and is pivoted at 16 to the associated sub-lever 14. Each

sub-lever is pivoted on a pivot wire 17 carried by a cross bar 18 fixed to the base of the machine. The upper end of each sub-lever carries a headed pin 19 which enters a slot 20 in the heel of the companion type bar. A segmental universal bar 21 supported for backward and forward movements on the segment is actuated by contacts 22 on the type bars. A rearward movement of the universal bar 21 transmits movement through arms 23 on said universal bar to arms 24 on a rock shaft 25, and from a centrally disposed arm 26 on the rock shaft to a link 27 to actuate the carriage escapement, as disclosed in the patent to Oscar Woodward, #1,342,489 dated June 8, 1920.

The parts as they are thus far described are the same as those employed in the Im-
20 proved #10 Remington machine. In said machine, however, the guide slots in the type bar segment are all cut in radial planes which correspond to the radial planes of movement of the body portions of the type bars, all
25 of said planes radiating from a common point of convergence of the type bars, which is the center of the arc defined by the pivot wire 8.

In accordance with my invention, as it is
30 disclosed in the present instance, I propose to maintain the gradually increased spacing of the slots from the center to the sides of the system, but to cut all of the guide slots 6 in planes that converge at a single off-set point
35 28 on the median plane α of the segment. This point is nearer the pivotal centers of the type bars than the center 9 of the arc defined by the pivot wire 8. The plane of movement of the heel of each type bar, or that
40 portion thereof received in its guide slot 6, is coincident with the plane of its slot; the planes of movement of all of the heels converging at the single point 28. On the other hand the body portion of each type bar is
45 bent laterally upwardly or outwardly of the plane of its slot. The result of this is that the body portion of each of said bars will not move in the plane of movement of its heel, but in a different plane and in printing position
50 all of the type bars will converge at a common center 9 corresponding to the center of the arc defined by the pivot wire 8, and the laterally bent body portions of the type bars will fan upwardly when at rest in the basket, as will hereinafter more clearly appear.

In carrying out my invention in the present instance, and in accordance with the specific showing of its embodiment disclosed herein, it is intended that all of the forty-
60 two type bars shall be mounted in off-set or off-centered slots as specified, although only a few of the type bars are illustrated to simplify the drawings.

In Fig. 2 the dotted lines 29 indicate planes
65 converging at the center 9 of the segment,

or the center of the arc defined by the pivot wire 8; each line cutting through its slot 6, whereas the dot and dash lines 30 indicate the planes of the off-set or off-centered slots 6. It will be observed that the planes 30 converge at a single point 28 off-set inwardly from the center of the segment, or off-set towards the pivot wire 8 from the center 9 of the arc defined by said pivot wire. By comparison of the two sets of lines 29 and 30, the extent of off-setting in the present arrangement of the planes of the slots 6 from the true radial planes of the segment may be readily observed.

After each type bar is mounted in place in its guide slot 6, it is bent laterally and outwardly or upwardly of the plane of said slot; the point of the bend being indicated at 31 in Fig. 2 and the line 32 crossing all of the type bars where such bends 31 occur. By this arrangement the body portions of the bars when in printing position converge at a common point 9, and all are properly received in the type bar guide 12 and strike at a common printing center 11. As each type bar returns to and remains in a state of rest in the basket, it assumes a different and higher position from what it would if mounted in a radial slot on a line 29 in the ordinary manner, as clearly indicated in the drawings. Instead of the body portion of each bar extending in a straight line fore and aft of the machine when at rest, the bars are slightly fanned in opposite directions from the center to the sides of the system, so that each type bar remains deflected slightly away from its adjacent bar, as indicated in Figs. 3 and 4. The type carrying ends of the terminal bars are therefore at a higher elevation in the basket than they would be if mounted in radial slots on the lines 29. This is clearly indicated at the left-hand side of Fig. 2 and in Figs. 3 and 4. It follows that more room is provided in the type rest for the system of type bars, and that a greater space is provided between each pair of adjacent bars to avoid the liability of conflict between them in their movements towards and from the type rest and at points adjacent thereto.

From the foregoing, it will be understood that in the construction as shown and described in the present instance, each type bar 5 may be said to comprise a heel or pivot end portion 33 included between the bend 31 and the rear end of the bar; a shank or body portion 34 between the bends 31 and 35, and a stem 36 from the bend 35 to the free end of the bar and on which stem the type block 37 is mounted. It will be seen, moreover, that the stem 36 is bent laterally at an angle to the body portion or shank 34, and that there is a slight lateral bend at 31 between said shank and the pivot end portion 33, so that each portion 33, 34 and 36 lies in a different plane and each shank 34 swings to

a common center 9, whereas its pivot end portion 33 swings in a plane divergent from said common center.

By cutting all of the slots 6 from a single off-set center 28, instead of cutting each of the slots on one side of the segment from a different center as in the construction disclosed in my patent hereinbefore referred to, I am enabled to bring about an adjustment between the segment and cutter around a single unvarying center and effect a cutting of the slots with greater speed and facility and with less liability of inaccuracy than in my former construction, thereby greatly facilitating the manufacture of the product.

Various changes may be made without departing from my invention.

What I claim as new and desire to secure by Letters Patent is:—

20 1. In a typewriting machine, a system of segmentally arranged pivoted type bars movable at their heels in converging planes, the point of convergence of such planes being on the median plane of the system and intermediate the pivots of the type bars and the point where the bars converge in the printing position.

25 2. In a typewriting machine, a system of pivoted type bars each having its heel moving in one plane and the body portion thereof in another plane, the planes of movement of the heels of all of the type bars converging at a single point on the median plane of the system and intermediate the pivots of the type bars and the point where the body portions thereof converge in the printing position.

30 3. In a typewriting machine, a system of type bars, and a slotted segment having its bearing slots converging at a common point on the median plane of the segment and offset inwardly from the center of the segment and in which slots the heels of the type bars are pivotally mounted, the body portion of each type bar being bent outwardly from the plane of movement of its heel and from

the plane of the companion slot in which it is mounted so that the type bars when in printing position converge at the center of the segment.

4. In a typewriting machine, a system of segmentally arranged pivoted type bars of uniform length, the heels of the type bars moving in planes which converge at a point on the median plane of the system off-set inwardly from the center of the arc in which the pivotal centers of the type bars are situated, the body portion of each bar being bent outwardly from the plane of movement of its heel so that the type bars in the printing position all converge at the center of said arc.

5. In a typewriting machine, a system of type bars of uniform length, a slotted type bar segment carrying an arc-shaped wire on which said type bars are pivoted, the planes of the bearing slots in the segment in which the heels of the type bars are mounted converging at a common point on the median plane of the segment off-set inwardly from the center of the arc defined by said pivot wire, the body portion of each bar being bent laterally from the plane of movement of its heel so that the type bars in printing position converge at the center of the arc defined by the pivot wire.

6. In a typewriting machine a system of segmentally arranged pivoted type bars a plurality of such bars at one side of the system having their heels moving in planes that converge at a single point in the median plane of the system below the point where the type bars intersect when in the printing position.

Signed at Ilion, in the county of Herkimer, and State of New York this 9th day of April, A. D. 1923.

GEORGE A. SEIB.
